UNITED STATES PATENT OFFICE.

JAMES M. STOCKER, OF ATLANTA, GEORGIA.

SPRAYER.

1,421,038.

Specification of Letters Patent. Patented June 27, 1922.

Application filed August 26, 1919. Serial No. 319,944.

To all whom it may concern:

Be it known that I, JAMES M. STOCKER, a citizen of the United States, residing at Atlanta, in the county of Fulton and State of Georgia, have invented certain new and useful Improvements in Sprayers; and I do hereby declare the following to be a full, clear, and exact description of the invention, such as will enable others skilled in the art 10 to which it appertains to make and use the same.

This invention relates to portable spraying apparatus, particularly to motor trucks provided with means for transporting and 15 distributing a liquid road binder of an asphaltic or bituminous nature.

The general object of the invention is to facilitate the operations of road building or surfacing wherein the solid road surfacing 20 materials such as broken stone, gravel, and the like, are bound together by a plastic binder applied in liquid state after the stone, gravel or the like has been distributed and shaped to the required surface contour.

Specific objects are to insure even spreading and uniform penetration of the binder over and into the road surfacing materials; to control accurately the quantity of binder deposited on any given area; to facilitate the 25 charging of the apparatus with the hot binder material; to regulate the quantity of the charge; and to improve the various details of structure of apparatus designed to achieve the objects of the invention.

The invention consists in the several combinations adapted to function in such manner as to carry out the purposes of the invention, and specifically described herein-after, illustrated in the accompanying drawings, and defined in the appended claims.

In the drawings, wherein similar reference characters designate similar parts throughout the several views:

Figure 1 is a side elevation of the apparatus with parts broken away to show constructions that would otherwise be concealed;

Figure 2 is a view of the rear end of the apparatus having parts broken away, and 50 also illustrating diagrammatically the action of the spray nozzles;

Figure 3 is a view of the filling pipes through which liquid is charged into the tank

A as seen looking in the direction of the arrows 3—3 in Figure 1;

55

Figure 4 is a sectional detail on line 4—4 of Figure 2;

60

Figure 5 is a fragmentary view, from above, of a portion of piping leading from the tank to the sprayer.

65

In the said drawings 10 indicates in general a truck or vehicle frame carrying a hood 11 housing the usual prime mover such as an internal combustion engine, said frame being mounted on suitable axles 12 and supporting wheels 13. Springs 14 support the weight of the rear portion of the frame and the load resting on it. It will be understood that, in practice, suitable transmission gear between engine and rear wheel will enable the apparatus to travel at any desired speed.

On the truck frame rests a tank A, adapted to contain the liquid to be sprayed.

A pipe E controlled by valve E' serves to admit liquid into the bottom of tank A. Said pipe E connects with branches E² and E³, extending laterally, each branch having valves E⁴ and E⁵, respectively. In filling tank A, liquid binder such as a hot bituminous or asphaltic substance may be pumped into it through pipes E² and E, or E³ and E, as may be most convenient. In practice, the liquid binder will be pumped, in a heated highly fluid state, from an asphalt melting furnace, which may be a portable furnace if desired.

Supported on the frame in front of tank A is an air compressor B, adapted to supply air under pressure to an air chamber or air tank D through the pipe N connecting the compressor with the air tank, the latter being of sufficient capacity to neutralize the effect of the pulsations of the compressor. An air pipe N' connects the air tank D with the dome A' of the tank A in order that compressed air may be admitted to said tank for the purpose of forcing the liquid therein through the spraying nozzles of the spraying header C to be presently described. Pipes N 90 and N' are provided with suitable valves N² and N³.

In the top of the dome A' is a small orifice G, through which air escapes as it becomes displaced by liquid being pumped into the 105 tank A through the liquid inlet pipes E², E,

- or E², E. In order to indicate when the tank is full, an audible signal device such as a whistle H, is so placed that air escaping through the orifice G will sound the signal.
- 5 The orifice G is adapted to be closed by a liquid-level responsive device such as a float I, said float being elevated by the liquid when the latter fills the tank to the level required so that a valve carried by said float
- 10 closes the orifice G. The whistle H, or other indicator, will sound continuously while liquid is being pumped into the tank and will stop when the required level is attained by the operation of the float I closing orifice G.
- 15 Cessation of the sound will indicate that the tank is full whereupon the pump will be stopped and valve E' closed.
- Connected with the pipe N' is a reducing valve or fluid pressure regulator O of any
- 20 suitable type. A check valve P is disposed in the pipe N' near the dome A' and between said dome and the pressure regulator O. Said check valve seats under the influence of pressure within the tank A and prevents vapors and fumes that may arise from
- 25 the hot liquid within the tank A from entering the pressure regulator O and fouling or gumming the mechanism thereof so as to interfere with its operation. The said pressure regulator O is so constructed and ad-
- 30 justed that it maintains a constant even pressure in tank A, regardless of the degree of pressure within the compressed air tank D, provided that the pressure in said air
- 35 tank is greater than the pressure in the tank A. The pressure of air in tank A is a most important factor in determining the rate of discharge through the spray orifices in the header C. If the pressure is not uniform in
- 40 said tank A the rate of discharge will not be uniform and the roadway treated will be of irregular structure and consistency. Furthermore, some sections of roadway require more binder than others and the quantity of
- 45 binder required is readily determined by the speed of travel of the spraying vehicle when the pressure in tank A remains constant. In the embodiment illustrated the air compressor is operated by the same prime
- 50 mover that drives the vehicle and may operate at somewhat different speeds at different times. The pressure regulator compensates for these varying rates of speed of engine and air compressor and maintains a
- 55 constant pressure in the tank. It is therefore only necessary to regulate accurately the speed of the truck in order to deposit a desired known quantity of binder per square yard of roadway.
- 60 The internal combustion engine or other prime mover (not shown) is supported by the frame beneath the hood 11 as stated. This prime mover is utilized for moving the vehicle, a transmission train of any com-
- 65 mon type connecting the motor with the

supporting wheels; and it is also utilized for driving the air compressor B. A driving shaft section L is connected to the crank shaft of the engine by a tumbling or universal drive-coupling L², and, by a similar coupling, section L is connected with a section L' journaled in bearings L³ on the frame. Between the bearings L³ a suitable pulley or other driving member L⁴ is secured to shaft section L', in the embodiment 70 illustrated, and the pulley L⁴ is belted to a wheel L⁵ that is carried on the drive shaft of the air compressor. It is contemplated that the air compressor shall be controlled by any suitable clutch mechanism (not 75 shown), so as to be coupled with or uncoupled from the shaft L'; or, if a belt drive be used, as illustrated, the belt thereof may be tightened or loosened by means of a belt tightener (not shown), all in a manner that 80 is well understood, in order that the vehicle may be moved from place to place without running the air compressor.

The gear casing K contains any approved form of variable speed transmission gearing 85 whereby the speed of the vehicle may be regulated. From the transmission gearing K any suitable driving train (not illustrated) may be connected to the drive wheels. In the construction disclosed the 90 shaft section L' runs at the same speed as the motor crank shaft, and as the speed controlling devices for stopping, starting and regulating the speed of the vehicle are rearward of the shaft L', the air compressor may 95 be run at top speed of the motor independent of the speed of travel of the vehicle.

Thus the vehicle may travel without running the compressor or the compressor may be operated without moving the vehicle, 100 from a single motor. The machine is so designed as to meet the maximum requirements when the transmission to the road wheels is in low, or slowest speed, and the motor running at substantially 90% of its 105 maximum speed; allowing a variation from normal maximum in either direction.

In practice, it is expected that the pressure in the compressed air tank D will be normally 30 to 40 lbs. per sq. inch greater 110 than that desired in the tank A, this difference insuring proper operation of the pressure regulator O, and maintaining a suitable reserve supply of air under pressure. With a liquid of a given viscosity the rate of 115 discharge in gallons per minute under a given constant air pressure may be readily determined. It then involves a simple calculation to determine at what rate of speed the machine must travel over the roadbed in 120 order to deposit the desired volume of liquid binder for each square yard of surface.

Besides the two factors of pressure and speed of travel over the ground, the viscosity, which in the case of asphaltic mate-

rials varies with variations of temperature, is a factor to be reckoned with in spreading any desired quantity over a given surface.

In building road surfaces with broken 5 stone or other road material bound with asphalt or like binder sprayed upon it, it is of great importance that the binder shall be evenly distributed over every part of the surface. It is also important to compensate 10 for the unavoidable varying temperatures and consequent viscosity changes of the binder. Every effort is, of course, made to maintain the temperature of the binder at all 15 times the same. But some variation cannot be avoided, owing to varying weather conditions. The spray-header is therefore made adjustable transversely of the center line of travel to enable a deposited stripe of binder to match with one previously deposited and 20 adjustable in height to compensate for variation in viscosity.

The spray header C consists of a pipe arranged horizontally and transversely at the rear of the truck frame and may have one, 25 two, or more rows of spray nozzles 20 communicating with it. Said spray header C is connected by transverse pipes Y to the pipes Y' parallel with the header C, said pipes Y' having adjacent ends coupled to a 30 T-coupling C'. An elbow C² is coupled to the said T-coupling C' so as to turn about a vertical axis, and a second elbow C³ is coupled to the elbow C² so as to turn a horizontal axis. A pipe Z extends from elbow 35 C³ to a double elbow coupling Z' in order to permit said pipe Z to swing vertically about its connection with a pipe section Z² extending upward to the tank A, said pipe Z² having a valve Z³. Valve Z³ is close to tank A 40 so that flow of liquid binder may be cut off close to the tank for the purpose of avoiding hardening or freezing of binder material in the pipe Z. A quick action valve Z⁴ is also located in the pipe Z, the said 45 valve Z⁴ having a handle Z⁵ extending upward in position to be conveniently manipulated by an operator standing or sitting on the rear portion of the apparatus, so that said operator may readily control the 50 charge of binder. The said mechanism comprises means whereby the spray header C may be shifted horizontally and raised or lowered at the will of the operator stationed on the rear of the vehicle; also means whereby, 55 at whatever height the spray header may be set, it will be automatically maintained at substantially the same height above the surface of the road, irrespective of the quantity of binder in the tank, or irrespective of 60 the distance between the tank and the rear axle, which is less when the tank is full than when it is empty, owing to the varying form of the springs 14 under light and heavy loads.

65 Extending rearward from the frame 10

are supporting bars consisting of parallel angle bars Q. Slides R are mounted on the bars Q and are movable fore and aft thereon. To the slides R is bolted a horizontal cross member V, which may serve as a platform if desired. Rising rigidly from each of the slides R is a pair of vertical guide arms R'. S represents a vertically movable guide member, there being one guided between each pair of guide arms R'. T represents a vertically movable slide box, there being one guided within each guide member S. The guide members S are of rectangular hollow form with open sides. The slide boxes T fit within the rectangular interior of guide members S and may be moved up and down therein by means of screw T' fixed to each slide boxes T, said screw passing upward through a hole in the top of guide member S and having a nut T² 75 threaded thereon, to which is rigidly connected a hand wheel T², by means of which the slide T may be raised or lowered with respect to the guide member S. Integrally formed with each nut T² is a sprocket 80 wheel, the sprocket wheels being connected by a sprocket chain T⁴ whereby both nuts T² are operated together, when either hand wheel T² is turned.

U indicates transverse slide bar members 95 connected in line with each other by a central toothed rack X. The members U are fitted to slide through the said slide boxes T without lateral play and move up and down with said slides in the guide member S. Engaging the teeth of rack X is an elongated toothed pinion W rigid with an upright shaft W' journaled in the cross member V, (upon which the operator may stand) said shaft having on its upper end a hand wheel 100 W², by means of which the shaft W' may be rotated, thereby shifting the rack X and members U to right or left through the slide boxes T. The extremities of the members U carry depending arms U' the ends of 105 which are provided with perforated bosses swiveled to the pipes Y' inside of and in lateral contact with the elbows connecting pipes Y' with pipes Y that communicate with the header C. By the construction 110 described it will be apparent that the header C, rack X and bar members U move in unison, and that any movement of said members U is imparted to header C. Thus, rotation of hand wheel W² to move the rack X 115 and members U endwise will move the header to the right or left with respect to the center line of advance of the vehicle, and movement of the slide T and bars U vertically will similarly move the header C 120 vertically, without disengaging pinion W from rack X owing to the length of the pinion teeth.

In order to hold the header automatically an even distance above the roadway, the 130

mechanism to be now described is provided:

At each side of the apparatus one end of a lever S' is pivoted at S^2 to a bracket secured to the rear axle of the vehicle. Said lever S' is fulcrumed between its ends at S^5 to a bracket Q' depending from each angle bar Q . The other end of the lever S' is pivoted to a lever arm S^3 rigid on a rock shaft S^4 pivoted in bearings secured to or 10 formed in the angle bars Q . An arm S^6 rigidly secured to the rock shaft S^4 is pivoted to a link S^7 depending from slide S^8 .

As the tank A becomes lighter by the discharge of its load the spring 14 tends to 15 resume its normal form and elevates the frame 10 and tank A accordingly. But as the frame 10 rises it elevates the rear end of lever S' by means of bracket Q' to which the lever is pivoted. Elevation of the rear 20 end of lever S' depresses the end of lever arm S^6 and draws guide member S downward. The slide box T and bar member U of course move with the guide member S and consequently move the spray header C 25 downward with respect to the frame 10 . When the frame 10 is elevated or depressed for any reason the spray header C is correspondingly moved in the opposite direction. The proportionate extent of the relative 30 movement will depend upon the proportionate lengths of the lever arms. It will be obvious that other specific devices may be substituted for the system of levers illustrated, and that, in general, the proportions of the 35 elements of the transmitting train will be such as to maintain the header C at substantially the same height above the roadway, or at such height as to spread the binder 40 evenly.

40 The desired height of the spray header C may be determined and set by the hand wheel T^2 and that same height will thereafter be maintained automatically even though the tank gradually rises and falls 45 as the load diminishes or increases by reason of the spraying of the contents of the tank A onto the road and repeated filling thereof.

It is most desirable to maintain the liquid 50 binder in the tank A always of the same viscosity, but bituminous or asphaltic materials pumped into the tank in a hot liquid condition gradually cool and become in consequence more viscous particularly in cold weather. When the liquid is hot and very 55 fluid it will cover a wider area when sprayed from a nozzle of given height above the roadway than when it is cooler. Consequently, the operator, stationed on member V at the rear of the vehicle, will adjust the 60 height of the spray header C so as to compensate for the changes of viscosity of the liquid, by raising or lowering the spray header C , and when said header has once been adjusted to the height necessary said 65 height will be automatically maintained.

In Figure 2 the effect of the spray at different heights above the roadbed is illustrated. At 1 the spray head is shown at the correct height above the road bed, the bases of the spray-cones just meeting and 70 effecting an even distribution of the binding material. At 2 the spraying nozzle is indicated as too near the road bed, the bases of the spray-cones not meeting and leaving 75 uncovered areas between them. At 3 the spray header is indicated as too high above the road bed, the bases of the spray-cones overlapping, making a streaky deposit on the road by reason of a too thick deposit where the bases of the cones overlap. By 80 watching the spray cones and their effect upon the roadway the operator is able to so adjust the spray header so as to produce the effect indicated at 1 in the diagram.

The binding liquid is deposited on the 85 roadway in broad stripes preferably parallel with the direction of the roadway. One zone of roadway having been covered another zone parallel therewith and adjoining it must be covered. It is practically im- 90 possible to drive a truck so accurately as to cause the second stripe of binder absolutely to meet the edge of the stripe or zone already formed. Hence the spray header C is made adjustable laterally as described. The 95 operator referred to, on the rear of the vehicle, watching the spray cones and the surface covered by them, may, by rotating the hand wheel W^2 , move the spray header C to the right or left and cause the stripe 100 of binder being deposited to match with the previously deposited stripe. The length of pinion W is sufficient to keep it in mesh with the rack X during the up and down movement of the latter.

105 In operation the apparatus will be driven to the source of supply of hot binder. The truck will be driven alongside the source of supply, either side, as may be more convenient, being presented to the supply vessel. A pump hose attached to a pump for transferring the material from the supply vessel to the tank A will be coupled to the end of pipe E^2 or E^3 , as the case may be, the valve E' opened and also the appropriate valve 110 on pipe E^2 or E^3 , the valve Z^2 being closed. As the binder material is pumped into tank A air will be displaced and forced out through vent G operating the whistle H . When the tank is filled the liquid level controlled float I will close the vent and the whistle cease to sound, thus informing the person in control that the tank has been 115 filled, and that the valve E' must be closed and the pump stopped.

120 The truck will then be driven to the place where the binding material is to be applied. The air compressor will be started in operation with the valves N^2 and N^3 opened, valve Z^3 open and valve Z^4 closed, and the 125

truck started over the zone of the road to be covered with binder material. The operator on the rear will open valve Z^4 , adjust the height of the spray header C to 5 the proper elevation and, by manipulation of the wheel W^2 will endeavor to keep the spray header following an even path, or depositing the binder in a stripe that leaves no uncovered streaks between it and a previously 10 made stripe of binder. The automatic adjusting devices maintain the spray header at the height above the surface at which the operator has set it by manipulation of the wheels T^2 .

15 The said pipe connections between header C and tank A permit the header C to be raised and lowered or moved transversely to the right or left. The movement of the header C to the right or left will cause the 20 T -coupling C' to describe an arc thereby varying the distance between the center of said coupling and the center of the pipe Z^2 at its connection with the tank A measured on a right line normal to said header between 25 said points. The up and down adjustments of said header will also vary the distance between said points. Adjusting mechanism for moving the header in the described directions is mounted on a support 30 slideable fore and aft to compensate for the described changes of position.

Having described my invention in such manner as to enable those skilled in the art to make and use the same what I claim and 35 desire to secure by Letters Patent is:

1. In combination, a truck carrying a tank 40 yieldingly mounted relative to the wheels of said truck, a sprayer connected with said tank, and automatic means for positioning said sprayer as the said tank rises or falls.

2. In apparatus of the class described, a 45 spring supported frame, a tank mounted on said frame, a sprayer, a pipe connection between said tank and sprayer, said pipe connection being constructed to permit of relative up and down movement between said tank and sprayer, and means responsive to the up and down movements of the tank for imparting opposite movement to the 50 sprayer.

3. In apparatus of the class described, a vehicle running gear comprising a supporting member, a frame yieldingly supported thereby, a tank mounted on said frame, a 55 sprayer, a pipe connection between said tank and sprayer, said pipe connection being constructed to permit of relative up and down movement between said tank and sprayer, a transmission train extending from the supporting member of the running gear to the sprayer, and connections between the yieldingly supported frame and said transmission train for converting the upward or downward movement of the frame into an 60 opposite movement of the sprayer.

4. In apparatus of the class described, a vehicle running gear comprising a supporting member, a frame yieldingly supported thereby, a tank mounted on said frame, a sprayer, a pipe connection between 65 said tank and sprayer, said pipe connection being constructed to permit of relative up and down movement between said tank and sprayer, a transmission train extending from the supporting member of the running gear to the sprayer, said transmission train comprising compound levers fulcrumed respectively on the supporting member of the running gear and on the yieldingly supported frame, and a connection between 70 the lever fulcrumed on said supporting member and the yieldingly supported frame.

5. In apparatus of the class described, a vehicle comprising a frame, a tank supported thereby, a sprayer, a conduit consisting of piping of rigid material connecting the tank with the sprayer, said conduit comprising a section having a hinged joint at each end, supporting means rigid with the frame above the sprayer, upright guiding means freely movable horizontally on said supporting means, a sprayer supporting means adapted to move up or down in said upright guiding means, sustaining connections between said sprayer supporting means 85 and the sprayer, and means whereby said sprayer supporting means may be moved up or down.

6. In apparatus of the class described, a vehicle comprising a frame, a tank supported thereby, a sprayer, a conduit consisting of piping of rigid material connecting the tank and sprayer, said conduit comprising a section having a hinged joint at each end, supporting means rigid with the frame above 90 the sprayer, guiding means movable horizontally on said supporting means, a sprayer supporting bar slideable endwise through said guiding means, sustaining connections between the slideable bar and said sprayer, and means whereby said sprayer supporting bar 95 may be moved endwise.

7. In apparatus of the class described, a vehicle comprising a frame, a tank supported thereby, a sprayer, a conduit connecting the sprayer and the tank, said conduit comprising a rigid pipe section having a universal joint at each end, supporting means rigid with the frame above the sprayer, upright guiding means on said supporting means, a slide box guided by said upright guiding means and adapted to move up or down, a sprayer supporting bar movable endwise in said slide box, sustaining connections between the sprayer and said bar, and 115 means whereby said sprayer supporting bar 120 may be moved endwise and up and down.

8. In apparatus of the class described, a vehicle comprising a frame, a tank supported thereby, a sprayer, a conduit connecting 125

- the sprayer with the tank, said conduit having two spaced apart flexible joints, supporting means rigid with the frame above the sprayer, upright guiding means movable 5 horizontally on said supporting means, a guide member adapted to move up and down on said upright guiding means, a slide box movable up and down in said guide member, sustaining connections between said slide 10 box and sprayer, hand operated means for adjusting the slide box with respect to said guide member and automatic means for adjusting the position of the guide member.
9. In apparatus of the class described, a 15 vehicle running gear comprising a supporting member, a frame yieldably supported thereby, a tank mounted on said frame, a sprayer, a conduit connecting the sprayer with the tank, said conduit comprising a 20 rigid pipe section having two spaced apart universal joints, supporting bars projecting rearward from the frame, horizontally movable, upright guide arms resting on said supporting bars, vertically movable guide 25 members guided by said upright guide arms, slide boxes guided vertically by said guide members, a transverse bar slidable endwise through said slide boxes, sustaining connections between said bar and said sprayer, 30 and controlling means for adjusting the slide
- boxes with respect to said guide members and for moving said bar endwise, and means responsive to the up and down movement of the frame for moving said guide members up and down in opposite directions. 35
10. In apparatus of the class described, a motor vehicle, a tank and spraying apparatus carried thereby, an air compressor adapted to create air pressure within said tank, a transmission train for driving the 40 vehicle, comprising speed varying mechanism, and driving connections from said transmission train to said air compressor, said driving connections extending from the driving train at a point between the speed 45 varying mechanism and the motor.
11. In apparatus of the class described, a motor vehicle, a tank and spraying apparatus carried thereby, an air compressor adapted to force compressed air into the 50 tank, a pressure regulator adapted to maintain a constant even pressure in said tank, a motor and transmission train for driving the vehicle, a speed regulating mechanism in said train, and driving connections from 55 said train to the air compressor at a point between the speed regulating mechanism and the motor.

In testimony whereof I affix my signature.
JAMES M. STOCKER.
